US0D1015528S

(12) **United States Design Patent** (10) Patent No.: **US D1,015,528 S**
(45) Date of Patent: ** Feb. 20, 2024

(54) **BATTERY-POWERED DENTAL FLOSSER**

(71) Applicant: **Jia Xi**, Shenzhen (CN)

(72) Inventor: **Jia Xi**, Shenzhen (CN)

(**) Term: **15 Years**

(21) Appl. No.: **29/806,652**

(22) Filed: **Sep. 4, 2021**

(51) LOC (14) Cl. **24-02**

(52) U.S. Cl.

USPC **D24/111**

CLAIM

The ornamental design for a battery-powered dental flosser, as shown and described.

DESCRIPTION

FIG. 1 is a perspective view of a battery-powered dental flosser showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
